UNITED STATES PATENT OFFICE.

JOHN ROY HILSTAD, OF BELVIDERE GARDENS, AND HARRY H. CANTERBURY, OF WHITTIER, CALIFORNIA, ASSIGNEES TO GEORGE G. GRIFFITH, OF MONROVIA, CALIFORNIA.

FENDER VISE.

Application filed December 16, 1924. Serial No. 756,274.

Our invention relates to vises particularly adapted, although not necessarily, for holding automobile fenders to facilitate repairing thereof, and a purpose of our invention is the provision of a fender vise having supporting arms which are adjustable to occupy any position desired and capable of being readily locked in any adjusted position whereby a fender can be firmly supported in any position and at any point or points along its length, so as to effect a firm securing of the fender to facilitate repairing and refinishing.

It is also a purpose of our invention to provide a fender vise in which the arms are adjustable independently of each other on a common mounting, while the mounting, in turn, is universally adjustable to effect simultaneous adjustment of the arms in addition to their independent adjustment. The mounting includes a ball associated with a socket capable of being contracted to secure the ball against movement and in any adjusted position.

We will describe only one form of fender vise embodying our invention and will then point out the novel features thereof in claims.

In the accompanying drawings,

Figure 1 is a view showing in side elevation and partly in section one form of fender vise embodying our invention;

Figure 2 is a vertical sectional view taken on the line 2—2 of Figure 1;

Figure 3 is a fragmentary view showing in side elevation the standard shown in the preceding views;

Figure 4 is a horizontal sectional view taken on the line 4—4 of Figure 1;

Figure 5 is a sectional view taken on the line 5—5 of Figure 1;

Figure 6 is a top plan view of the vise with the fender removed.

Figure 7 is an enlarged fragmentary view of the ball constricted sockets and one of the flexing bolts;

Figure 8 is a transverse section on line 7—7 of Figure 1, illustrating the locking means for one of the adjustable arms.

Similar reference characters refer to similar parts in each of the several views.

Referring specifically to the drawings, our invention, in its present embodiment, comprises a standard 15 having threadedly associated therewith a base 16, the latter adapted to be secured to the floor in any suitable manner so as to rigidly support the standard in

an upright position. The standard 15 is, in the present instance, of tubular form, its upper end being provided with the lower section 17 of a ball socket. This socket section 17 may be cast integrally with the standard or formed separately therefrom and secured in any suitable manner to the standard. The other section of the socket, designated at 18, is provided with a flange 19 through which a pair of bolts 20 extend for supporting the socket section for limited movement to occupy one position in which a ball 21 can be freely moved within the socket and another position in which the socket is constricted to lock the ball against movement. The bolts 20 have threaded engagement with bosses 22 formed on the standard 15, and these bolts are provided with nuts 23 at points above and below the flange 19 which, when properly adjusted, serve to securely clamp the flange to the bolts. The bolts 20 are of sufficient length to allow a slight flexing thereof, as clearly illustrated in Figure 7, to permit the movement of the socket section 18 to constricted position in effecting a locking of the ball against movement. The inherent resiliency of the bolts is sufficient to return them to perpendicular position when the socket section is relieved of the force necessary to move the latter to constricted position so that the socket section 18 will automatically move to non-constricting position to permit an adjustment of the ball.

The movement of the socket section 18 from normal to constricted position is effected through the medium of a rod 24 mounted for vertical movement in an ear 25 formed on the standard 15 and adjustably associated with the flange 19 through the medium of nuts 26. This rod 24 is provided at its lower end with a yoke 27 bifurcated to accommodate an arm 28 formed on the standard 15 and to permit of the necessary vertical movement of the rod. A cam lever 30 is pivoted in the yoke at a point below the arm 28 so as to engage the arm when rotated to thereby effect a downward movement of the rod against the action of a spring 31 interposed between the flange 19 and the ear 25. This spring 31 normally urges the rod 24 upwardly so that the upper socket section 18 can occupy a released position with respect to the ball 21. However, when the cam lever 30 is moved to the position shown in Figure 1 it will operate to draw the rod downwardly and thereby move the socket section to constricting position to

effect a locking of the ball 21. A pin 27^a is extended through the arm 28 to prevent accidental displacement of the yoke 27 from the arm, as will be understood.

The ball 21 constitutes part of a mounting for a pair of supporting arms 32 and 33, and the remainder of the mounting is made up of an extension 34 formed on the ball 21 and extending through a suitable opening 10 formed in the socket section 18. This extension 34 is provided with an ear 35 formed on opposite sides with threaded studs 36 and 37, the latter being longer than the former, as clearly shown in Figure 2. The arm 32 and 15 33 are curved longitudinally, as shown in Figure 1, and transversely, as shown in Figure 6, so that the two clamping heads 38 formed on the upper ends of the arms will be disposed in the same vertical plane. The 20 lower ends of the arms 32 and 33 are provided with supporting heads 39 and 40, respectively, loosely mounted upon the studs 36 and 37, with fabric washers 41 interposed between the heads and the ear 35 for the purpose 25 of setting up the necessary friction to prevent accidental movement of the head on the studs. Clamping nuts 42 and 43 threadedly engage the studs 36 and 37, respectively, for moving the heads 39 and 40 into clamping 30 engagement with the ear 35 so as to lock the arms 32 and 33 against movement on the mounting. These nuts are provided with handles 44 which facilitate the manual manipulation thereof, as will be understood.

35 The stud 37 projects beyond the nut 42 for the purpose of receiving a nut 45 constituting a support for a ball 46. A ball socket 47 is formed on the lower end of a bracing arm designed to brace a fender supported by the 40 arms 32 and 33 at any point along its length. This bracing arm includes a rod 48 carrying the socket 47 to receive the ball 46 and to thereby allow universal adjustment of the rod on the ball. The rod 48 is telescopically 45 associated with a tubular rod 49 carrying a set screw 50 provided with a winged head 51 by means of which the screw can be manipulated to firmly grip the rod and thus secure the tubular rod in any extended position desired. The upper end of the tubular rod 49 55 is provided with a ball 52 on which is mounted a socket 53 fixed to the stationary jaw 54 of a miniature vise so that the vise as a unit is capable of universal movement upon the tubular rod. The movable jaw 55 is pivoted on the stationary jaw 54 and is capable of adjustment through the medium of the bolt 56 and the wing nut 57, it being understood that a spring (not shown) is interposed between 60 the jaws for normally urging the movable jaw outwardly from the stationary jaw.

As the two clamping heads 38 are identical in construction a description of one will suffice for both. Each clamping head 65 comprises a stationary jaw 38^a fixed to or formed

integral with the corresponding arm 32 or 70 33, and a movable jaw 38^b mounted upon a stud 38^c threaded at one end to engage within the jaw 38^a and provided at the other end with a handle 38^d by which the stud can be rotated in effecting movement of the jaw 38^b. A coiled expandable spring 38^e is interposed between the jaws for normally urging the movable jaw outwardly from the stationary jaw, so that as the stud is unscrewed a separation of the two jaws will be effected. To prevent marring of the fender when engaged by the clamping head, washers or disks 38^f are interposed between the jaws in the manner clearly shown in Figure 5, so as to 80 grip the fender, as will be understood.

In practice, the supporting arms 32 and 33 can be adjusted upon their mounting and independently of each other by manipulation 85 of the nuts 42 and 43 to release the supporting heads 39 and 40, when the arms can be swung about the studs 36 and 37, as centers, to occupy any position desired in a vertical plane. In this manner, the spacing of the clamping heads 38 can be effected to grip the flange of a fender at any desired point along its length so as to securely hold the fender in position for refinishing or repairing. Operating in conjunction with the arms 32 and 33 is the bracing arm including the elements 48, 49, and the miniature vise, the latter being secured to another flange of the fender, as 90 illustrated in Figure 2, whereby an additional support for the fender is provided. The extensibility and universal mounting of the 95 bracing arm permit of its being moved and clamped to the fender at any point desired so as to properly co-operate with the arms 32 and 33 and providing a rigid support of the fender. 100

Should it be desired during the repairing or refinishing of the fender to move the fender bodily from the position shown in Figure 1, so that any particular portion of the fender may be conveniently positioned for working, the ball 21 which is normally locked by the normally constricted socket can be released by swinging the cam lever 30 so as to disengage the arm 28 whereby the inherent tendency of the bolts 20 to return to 115 their normal perpendicular position will operate to elevate the upper socket section 18 sufficiently to permit unrestricted movement of the ball so that the entire mounting for the arms 32, 33, as well as the bracing arm, can 120 then be shifted to any desired position and then locked in such position by a return of the cam lever to the locking position shown in Figure 1. By virtue of the ball and socket mounting, it will be manifest that the several 125 arms can be moved in any vertical or horizontal plane so that the fender can be caused to assume an infinite number of positions, thus greatly facilitating repairing of the fender. 130

In order to facilitate bending of a fender back to its original curvature where it is necessary to exert a push or pull on one part of the fender while the other part is firmly held against movement, we provide means by which one of the arms 32 or 33 can be positively locked against movement on the ear 35 while the other arm is free to be moved. This means comprises in the present instance a lug 60 (Figure 1) fixed to the ear 35, and a second lug 61 movable on the arm 32 to engage or disengage the stationary lug 60. The lug 61 is provided with a slot 62 through which a stud 63 extends, the latter being fixed to the arm 32 and receiving a winged nut 64 by which the lug can be clamped in any longitudinally adjusted position. With the lug 61 in the position shown in Figure 1, the arm 32 is locked against movement in a clockwise direction, and with its clamping head 38 secured to a fender, it will be clear that that portion of the fender engaged by the clamp will be held against movement in the direction of the arm 33, while the arm 33 is free to be moved to cause a bending of the fender, assuming that the nut 43 has been previously loosened. It is to be understood that the lug 61 can be moved to engage the opposite side of the lug 60, thus locking the arm 32 against movement in a counter clockwise direction and thereby firmly holding one portion of the fender against movement away from the arm 33.

Although we have here shown and described only one form of fender vise embodying our invention, it is to be understood that various changes and modifications may be made without departing from the spirit of the invention and the spirit and scope of the appended claims.

We claim as our invention:

1. A fender vise comprising a plurality of arms, clamps carried by the arms, means for supporting the arms for independent adjustment about a horizontal axis, a ball secured to said means, a two-part socket receiving the ball, one part of said socket being normally urged to an expanded position wherein unrestricted movement of the ball in the socket can be effected, and cam actuated means for moving said part to effect a constriction of the socket whereby a locking of the ball against movement is effected.

2. A fender vise comprising a plurality of arms, clamps carried by the arms, a mounting for the arms including a ball, a socket receiving the ball and normally expanded to allow universal movement of the ball but capable of being contracted to secure the ball against movement, and cam actuated means for contracting the socket and maintaining the same in contracted position.

3. A fender vise comprising a standard, a two-part socket on the standard, one part of said socket being secured within the standard,

means capable of being flexed supporting the other part of the socket in a manner to allow limited movement of said part, a ball within the socket, arms adjustable on the ball, a rod operatively connected to the movable part of the socket, and manually operable means for moving and then holding the rod in a manner to move and hold the movable part of said socket to effect a locking of the ball.

4. A fender vise comprising a standard, a two part socket on the standard, one part of said socket being secured within the standard, means capable of being flexed supporting the other part of the socket in a manner to allow limited movement of said part, a ball within the socket, arms adjustable on the ball, a rod operatively connected to the movable part of the socket, and cam means for moving and then holding the rod in a manner to move the movable part of said socket to effect a locking of the ball.

5. A fender vise comprising a universal mounting, cam actuated means for locking the mounting in any adjusted position, arms mounted for independent adjustment on said mounting, and one of said arms being extensible.

6. A fender vise comprising a plurality of arms adjustable about a horizontal axis each comprising a stationary jaw formed integral with the arm, a stud threadedly mounted in the stationary jaw, a movable jaw on the stud, and means for urging the movable jaw outwardly from the stationary jaw.

7. A fender vise comprising a plurality of arms, clamps carried by the arms, means for supporting the arms for adjustment about a horizontal axis, and a bracing arm mounted for universal movement about said horizontal axis.

8. A fender vise as embodied in claim 7, wherein the bracing arm is extensible and provided with a vise.

9. A fender vise comprising a standard, a two part socket on the standard, one part of the socket being secured within the standard, a ball within the socket, arms adjustable on the ball, means on the standard for constricting the socket and maintaining the same in constricted position, and means for supporting the arms for adjustment about a horizontal axis.

10. A fender vise comprising a plurality of arms, clamps carried by the arms, means for supporting the arms for independent adjustment about a horizontal axis, and a ball and socket mounting for said means in which the socket is capable of being constricted to effect a locking of the ball in adjusted position whereby universal adjustment of said means is effected.

11. A fender vise as embodied in claim 10, wherein the socket is yieldably urged to released position.

12. A fender vise comprising a plurality of

arms, clamping heads carried by the arms, means for supporting the arms for adjustment about a horizontal axis, a bracing arm mounted for universal movement about said horizontal axis, and means for locking the arms in any adjusted position.

13. A fender vise as embodied in claim 12, wherein a vise is universally connected to the bracing arm.

10 14. A fender vise as embodied in claim 12, wherein the bracing arm is extensible and a vise is universally connected thereto.

15. A fender vise as embodied in claim 12, wherein the bracing arm comprises telescoping rods, and a vise is universally connected to one of the rods.

16. A fender vise comprising a standard, a two part socket on the standard, one part of said socket being secured within the standard, means capable of being flexed supporting the other part of the socket in a manner to al-

low limited movement of said part, a ball within the socket, arms adjustable about a common axis on the ball, and means connected to the standard for moving the movable part of said socket against the action of said means to effect a constriction of the socket and as a consequence locking the ball against movement.

17. A fender vise comprising a standard, a two part socket on the standard, one part of the socket being secured to the standard, means capable of being flexed supporting the other part of the socket to allow limited movement of said part, a ball in the socket having arms mounted thereon, and means for moving the movable part of said socket against the action of said means to effect a constriction of the socket and hence the locking of the ball against movement.
